ANNUNCIATOR

Ernest G. De Valera, New York, N. Y.

Application August 27, 1934, Serial No. 741,601

2 Claims. (Cl. 177—327)

This invention relates to electrically operated annunciators in general, and particularly to the kind equipped with visible and audible annunciator means.

5 The prime object of this invention is to provide a self-resetting annunciator.

Another object of this invention is to provide a device of this type which is not only inexpensive in construction, but extremely simple in design, manufacture, and operation and which will effectively respond, when being energized.

10 Another object of this invention is to provide a construction of grouped, individual solenoids provided with individual armatures connected with one another and operating in unison, and adapted to actuate visible annunciator elements without the requirement of annunciator restoring mechanisms, such as hand levers, or similar devices for restoring the elements to their 15 normal or inoperative position.

Another object of this invention is to provide in connection with such visible annunciator elements, an audible annunciator of a simple, inexpensive and effective construction, adapted to 20 operate in conjunction and simultaneously with said visible annunciator elements.

The foregoing and still further objects of the present invention will become more fully apparent from the ensuing description and the accompanying drawing, the latter forming diagrammatical illustrations of one of the many possible arrangements of the present invention, and which drawing obviously is intended for explanatory purposes only, without limiting this invention to the actual showing. In the drawing:

Fig. 1 is a diagrammatical plan view of my device,

Fig. 2 is a partial front elevation thereof, and

40 Fig. 3 is a modified form of a casing employed in connection with my device, and

Fig. 4 is a modified form of the construction of my device, held purely diagrammatically.

In the figures, numeral 10 denotes a source of energy, shown in the form of a battery, but which 45 may readily be substituted by a transformer or a direct line connection. From one end of the electric power source extends a conductor 11 leading to the terminals 12, 12' and 12'' of individual energizing switches, which may be disposed at 50 different localities. The other end of the power source is connected by means of conduit 13 to solenoid 14 of an audible annunciator, and from there the connection continues through conduit 15 to one end of solenoids 16, 16' and 16''. The 55 other end of the solenoids are connected by means

of conduits 17, 17' and 17'' to the other terminals 18, 18' and 18'' of the switches.

Passing through the hollow interiors of solenoids 16, 16' and 16'' is a tubular member 19 preferably made of brass or any other non-magnetic material. This tubular member serves as spacer and connector for the solenoids and is provided with longitudinal slots 20 and 20', the purpose of which will be explained presently.

Within tubular member 19 there is operatively 10 mounted a series of individual armatures 21, 21' and 21'', corresponding in numbers to that of the solenoids, and being connected with one another and at the same time spaced from each other by means of non-magnetic connectors 22. 15 From these connectors extend carriers 23, supporting visible annunciators 24, 24' and 24''. These annunciators are preferably mounted in registry with their respective armatures 21, 21' and 21''. The entire mechanism is enclosed in a 20 casing 25 provided with transparent windows or ports 26, 26' and 26'', which ports are in registry with the centers of solenoids 16, 16' and 16''. 25

The audible annunciator consists of solenoid 14, wound about a tubular member 27, in which latter is placed a resilient member 28 in the form of a spring. At both ends of the spring are provided balls 29 and 29', made of magnetic material, and next to the balls at the end of the solenoids are provided sound producing abutments 30 and 30'. In abutment 30 there is shown an adjusting screw 31 adapted to control the movement of balls 29 and 29' by controlling the tension of spring 28.

At the connection of conduit 15, leading from the solenoid 14, there is arranged an interrupter marked 32, intended for use when direct current is employed. When alternating current is available, either through a transformer or directly, this interrupter may be omitted.

I prefer to make the visible annunciator elements from differently colored material, or provide them with numerals or other means of distinguishing them. They may be either opaque or transparent, and when transparent a light source 45 may be employed behind them in order to make them more distinctly visible. For this purpose I may employ either a neon lamp (not shown) extending over the entire interior of the casing behind ports 26, 26' and 26'', or I may employ 50 individual electric bulbs mounted directly behind each of the ports and adapted to be individually operated in unison with each of the individual solenoids.

In Figure 1 I have illustrated in broken lines 55

an arrangement of electric bulbs and their connections which are shown to be mounted in parallel with their respective solenoids. Secured to lead 13, at 33, is a conduit 34 connected with one terminal of each of the bulbs 35, 35' and 35''. To all leads connected with contact arms 18, 18' and 18'' of the switches are joined suitable conduits 36, 36' and 36'' leading to the other terminals of the bulbs. Thus when any one of the contacts 12 and 18, 12' and 18' and 12'' and 18'' are pressed together, their respective solenoids will be energized and at the same time their respective bulbs will be caused to light up. When thus energized the armatures of the energized solenoids will be drawn thereinto and cause the respective visible annunciator element to move into registry with one of the ports of the casing, and will be illuminated by the energized bulb behind it. At the same time the audible annunciator will be energized and will emit a sound attracting attention to the annunciator.

The operation of the audible annunciator is a very simple one. The moment current flows through the solenoid 14 balls 29 and 29' are drawn inwards. When the flow of current stops, spring 28 moves the balls against the sound producing abutments 30 and 30'. When alternating current is used the interruption of the current is natural. When direct current is employed an interrupter 32 is required. That interrupter is directly operated by one of the balls, as clearly shown in Figure 1.

When the operation of one of the solenoids is completed, that is, when one of the switches is released, the visible annunciator brought in registry with its respective port of the casing remains in that position until another of the solenoids is energized. By actuating another of the switches, the armatures will be moved, and another annunciator will appear behind its respective port. In the event the same switch is operated twice the annunciator will remain in its first assumed position.

In the drawing I have illustrated a row of three solenoids arranged in a substantially straight line. It is obvious however that their relative position may be changed, and that instead of arranging the solenoids in a straight line they may be grouped in a curve, in a circle or in any other convenient manner, as long as their armatures are moved together in such a way that only one of the visible annunciators will appear in back of one of the ports.

In order to save space and prevent interference of one visible annunciator with the other, they may be arranged in the manner indicated in Figure 3, one above and two below, or vice versa.

The movements of the armatures in the solenoids may be controlled in different ways and it is not absolutely necessary to employ only three such solenoids in a row, but any number of solenoids and armatures may be grouped together so that the moment one of the solenoids is energized, only the corresponding visible annunciator element moves in its predetermined place.

The audible annunciator is shown in a very simple construction, and its end plates or sound producing abutments are held in a concise design in order to save space. It is obvious however that these abutments may take the form of bells or similar devices which will produce a more audible sound than plates 30 and 30' shown.

Referring now specifically to Figure 4, numerals 37, 37' and 37'' denote three individual solenoids, adapted to be connected rigidly with

one another and spaced in the same way as illustrated in Figures 1 and 2. There is again seen an armature comprising individual armature members 38, 38' and 38'' which are connected with, and spaced from one another by means of non-magnetic spacers 39 and 40. From these spacers project the usual carriers or extensions 41 and 42. In this construction the extensions do not support the visible annunciators, directly, but function in a somewhat different manner.

Independently of the armature are provided fixed pivotal points 43 and 44, which may be in the form of brackets extending from the casing, at which pivotal points are operatively supported by means of levers 45, 45' and 45'' visible annunciator elements 46, 46' and 46''. These supporting levers are connected with operating levers 47 and 48, which latter engage extensions 41 and 42, respectively. For each annunciator element there are provided the usual ports 49, 49' and 49''.

The levers and the annunciators are shown in this figure in various positions. The full lines denote the position of levers and annunciator elements when solenoid 37 is energized. The broken lines, marked I, indicate the position of the levers and the annunciator elements assumed when solenoid 37'' is energized, and the broken lines, marked II, of the middle annunciator element and its levers indicates the position of the middle annunciator element when solenoid 37' is energized.

The above described illustration is intended to show that the annunciator elements do not have to be carried directly by extensions 41 and 42, as is the case in the previously described form of my device, but that the elements may be operated by a lever arrangement entirely independent of the solenoids and the armatures. It is quite obvious that any other element actuating construction may be employed for achieving the same results of automatically and simultaneously changing the positions of all annunciator elements, and of causing only that annunciator element to become visible, the corresponding solenoid of which has been last energized, while all other annunciator elements become invisible until their respective solenoids are energized. In order to assure proper operation of my device, the solenoids as well as the armatures are grouped to form units, which are fixedly held together, while the individual members of each unit are suitably spaced from one another. This applies to any desired grouping or arrangement previously mentioned, irrespective of the type of construction employed for actuating the annunciator elements.

From the foregoing it is quite evident that my invention is capable of a great many variations, changes and improvements and I wish it to be understood that I shall have the right to make such changes and improvements within the broad scope of my invention, as defined by the annexed claims.

I claim:

1. An annunciator of the class described, comprising in combination, a casing provided with spaced transparent ports, a plurality of individual, spaced solenoids mounted in alignment within the casing, a tubular, non-magnetic member on which said solenoids are mounted, provided with slots extending between each two adjacent solenoids, a plurality of spaced individual armatures slidably mounted in said tubular member, non-magnetic means connecting said armatures, carrier means extending from said

75 70 65 55 45 35 25 15 10

5 armature connecting means through said slots of the tubular member, a plurality of spaced visible annunciator elements supported by said carrier means, said annunciator elements being spaced at predetermined distances from each other, different from the spacings between the ports.

10 2. In an annunciator, a plurality of individually energizable, aligned and equally spaced solenoids, a non-magnetic, tubular member serving as mounting and spacer for said solenoids and provided with slots extending from one solenoid to the other, a plurality of individual, interconnected armatures, one for each solenoid, operatively disposed within said tubular member, said armatures being aligned and equally spaced at distances different from those separating the solenoids, rigid spacing means connecting said armatures, spaced annunciator elements, one for

each solenoid, secured to the spacing means of said armatures, by means of extensions projecting through the slots of said tubular member, said elements corresponding as to their positions and spacings to the positions and spacings of said 5 armatures, a casing enclosing said solenoids and annunciator elements and provided with ports, corresponding as to their spacings to that of said solenoids, the relative spacings of said elements, armatures, solenoids and ports being such that 10 when one solenoid is energized, its corresponding armature will be operated and will cause the corresponding annunciator element to assume a pre-determined, for instance, visible position in back of the port corresponding to the energized 15 solenoid, while all other annunciator elements are moved to an invisible position.

ERNEST G. DE VALERA.
